United States Patent Office

Des. 217,571
Patented May 12, 1970

217,571

PACKING MACHINE

Joseph L. Arcudi, Elizabeth, and John W. Rathemacher,
Navesink, N.J., assignors to Becton, Dickinson and
Company, Rutherford, N.J., a corporation of New
Jersey

Filed May 9, 1969, Ser. No. 17,096

Term of patent 14 years

Int. Cl. D15—05

U.S. Cl. D55—1

FIG. 1 is a front elevational view of a packing machine showing the new design;

FIG. 2 is a top plan view thereof;

FIG. 3 is an elevational view of one side of the machine, and

FIG. 4 is an elevational view of the other side of the machine.

We claim:

The ornamental design for a packing machine, as shown and described.
